UNITED STATES PATENT OFFICE.

HARRY L. HAMMOND, OF INDIANAPOLIS, INDIANA.

WINDOW-FASTENER.

No. 874,586.

Specification of Letters Patent.

Patented Dec. 24, 1907.

Application filed August 13, 1907. Serial No. 388,299.

To all whom it may concern:

Be it known that I, HARRY L. HAMMOND, a citizen of the United States, residing at Indianapolis, in the county of Marion and State of Indiana, have invented certain new and useful Improvements in Window-Fasteners, of which the following is a specification.

This invention relates to a device for fastening windows; and the object of the invention is to provide a window fastening device which will be extremely simple in construction, inexpensive to manufacture, and neat in appearance.

I accomplish the objects of my invention by a window fastening device illustrated in the accompanying drawings, in which—

Figure 1 is a fragmentary detail view in perspective of a window-casing, showing my improved fastening device in operating position. Fig. 2 is a central vertical sectional view through a portion of the window-sash and frame. Fig. 3 is a transverse sectional view of one side of the window-casing, on an enlarged scale, showing by means of the full lines the sash fastener in operating position, and by means of the dotted lines its open position.

In the drawings, 1 constitutes an ordinary window-frame or casing, 2 the upper sash, and 3 the lower sash. The frame is provided with the parting-strips, etc., all of which is old and well known.

My fastening device consists of a narrow piece of material 5, either wood or metal, which is secured by means of the hinges 6 to the inner guide strip 7 secured to the window casing 1. The strips 5 may be placed on each side of the casing 1 so that greater security is afforded. The strips 5 are of a length to extend from the upper edge of the lower sash, when closed, to the upper end of the window-frame 1. By means of the hinge mounting of the strips 5 they may be swung in over the upper edge of the lower sash when the latter occupies an extreme

lower position, and when the strips 5 are turned outward, as shown in the dotted position in Fig. 3, the lower sash may be moved upward.

To prevent the upper sash 2 from being lowered I provide said sash with little blocks or circular disks 10 which are secured to the inner surface of the sash and near its upper end. The blocks or disks 10 when in position form projecting shoulders which are engaged by the shoulders 11 formed on the strips 5 by providing the upper ends of the strips with recesses, which permit said strips to be closed. The blocks 10 are preferably formed round so that sharp corners are eliminated. It will be noted that when the strips 5 are closed the corners 11 will move in under the lower edge of the disks 10 and thus prevent the upper sash from being lowered. It will be noted that the strips 5 when in closed position are hardly noticeable and do not look unsightly or mar the window-frames. To make the fasteners less conspicuous they are generally made to harmonize with the finish of the room in which they are used.

Having thus fully described my said invention, what I desire to secure by Letters Patent, is—

In a window fastening device, the combination with the casing and sash, of a movable strip hingedly secured to the casing and susceptible of being moved over the upper edge of the lower sash and extending to and abutting the upper end of the window-casing, said strip being provided with a notch, and means on the upper sash adapted to engage the notch on the strip.

In witness whereof, I, have hereunto set my hand and seal at Indianapolis, Indiana, this 6th day of Aug., A. D. one thousand nine hundred and seven.

HARRY L. HAMMOND. [L. S.]
